APPARATUS FOR PRODUCING ONE-PIECE MULTIFOCAL LENS BLANKS

Frank E. Duckwall, Indianapolis, Ind., assignor to Continental Optical Company, Inc., Indianapolis, Ind., a corporation

Original application May 17, 1940, Serial No. 335,810. Divided and this application April 15, 1941, Serial No. 388,657

7 Claims. (Cl. 51—127)

This invention relates to the apparatus and method employed in producing one-piece bifocal or trifocal lens blanks and lenses, and particularly that type of lens having a non-circular segment for providing the near vision field, and in some modifications, an intermediate vision field, being a division of my copending application, Serial No. 335,810, filed May 17, 1940, for "Apparatus and method for producing a one piece multifocal lens blank and lens."

In the actual commercial production of such lenses, it has been found that the use of a cam button secured to the lens for directly controlling and guiding the grinding and polishing buttons is the most practical and satisfactory means of producing such a lens. But in the use of such cam button, difficulty has been experienced in conforming the grinding and polishing action to the exact boundary line or demarcation between the two fields. This is for the reason that where-in the cam button lies on said line, it is impossible to carry the grinding operation sharply thereto, since a film of rouge and dust becomes interposed and embedded about the cam button, resulting in a minute depressed groove being produced which may be due to the wedging action of the cam and button.

To overcome the above, there is employed an undercut cam button having a raised tool engaging cam of the area and shape desired for the finished near vision field, and spaced from the surface thereof by a securing block spaced inwardly from its tool engaging surface.

It is the purpose of this invention to provide a method and apparatus for accurately positioning the cam upon the lens blank and securing it thereto, and particularly a cam button of the above-described character.

The full nature of the invention will be understood from the accompanying drawings and the following description and claims:

Fig. 1 is a plan view of a lens blank with the inner and outer surfaces rough ground.

Fig. 2 is an enlarged section taken on the line 2—2 of Fig. 1.

Fig. 3 is the same as Fig. 2, showing a modified form.

Fig. 4 is the same as Fig. 1 showing the cam button secured over a portion of the inner field.

Fig. 5 is an enlarged section taken on the line 5—5 of Fig. 4.

Fig. 6 is a plan view of the finished lens showing the finished non-circular inner field in full lines and the removed portion thereof in dotted lines.

Fig. 7 is a plan view of the cam button centering device.

Fig. 8 is a section taken on the line 8—8 of Fig. 7.

In the drawings, there is illustrated a full uncut lens blank 10 upon which there has been roughly ground a distance vision field A and a centrally ground and finished concentric inner near vision field B.

10 In the manner hereinafter described, a cam button 11 is secured to a portion of the field B, as illustrated in Figs. 4 and 5, said button having a tool-engaging cam surface 12 spaced above the surface of the blank and secured thereto by an 15 inset block portion 13. The cam surface 12 is of the shape desired for the finished segment of the lens which comprises the inner near vision field, whereby a grinding or polishing tool may be applied to the exposed surface of the blank for 20 grinding and polishing said surface to produce a one-piece bifocal lens having a non-circular near vision field B, as shown in Fig. 6.

In this operation, that portion of the blank indicated by dotted lines in Fig. 5 is ground and 25 polished away to provide the finished distance vision field A', leaving a shoulder 14 and a merged arcuate boundary line 15 between the fields of the finished lens, the shoulder portion 14 being substantially flat and located at approximately the 30 optical center of the two fields for minimizing the image jump therebetween.

As previously stated, the problem here involved, and to which this invention is directed, lies in the complete elimination of any vestige of the 35 original boundary line indicated at 16, while simultaneously effecting the smooth merging of the fields along the arcuate boundary line indicated at 15.

For securing the cam button to the lens, it is 40 provided with a substantially centrally positioned orifice 17 extending therethrough, through which a cementing shellac is introduced when the cam has been accurately positioned. For positioning the cam, reference is made to Figs. 7 and 8 illustrating the cam setting tool. After the cam has 45 been set by said tool and the shellac poured in place, the tool with the blank is placed in a suitable furnace and heated so that the shellac passing from the orifice 17 between the adjacent surfaces of the cam button and lens, will be hardened 50 in place to firmly cement it.

The cam setting tool comprises an annular holder 20 having a peripheral seat 21 upon which the blank 10 is placed. Vertically movable arms 55 22 are mounted for vertical adjustment upon the

wall of the holder and locked by the wing nuts 23 so that each arm may be moved vertically with respect to the holder and locked in adjusted position.

Slidably mounted on each arm there is a block 24 having a ball and socket connection 25 with a cam positioning head 26, the head being held in extended position with respect to the block under tension of a spring 27. Said positioning head, through the block, is adjustable radially of the blank and longitudinally of its supporting arm 22 by an adjusting screw 28 having threaded engagement with the block 24 and rotatably supported by a bearing 29 extending longitudinally of the arm 22. Said screw 28 has secured thereon for adjusting purposes a thumb nut 30.

Upon the blank being mounted in the holder 20, the operator, by means of a magnifier and proper illumination, adjusts the heads 26 to a position so that their blank engaging edges accurately lie tangentially with three segments of the boundary line 16 about the inner field B, as shown in Fig. 7. The operator then selects a cam button 12 of the proper size to snugly fit between the three positioning buttons 26. Since in grinding the field B, there may be some slight variation in diameter, the operator is provided with several buttons 12 of slight variation in size, selecting the button which most closely fits within the positioned heads 26.

With the button 12 so positioned, and while snugly nesting between the heads 26, the shellac is poured into the aperture 17 and the entire cam locating tool is placed in the furnace to effect the hardening of the shellac to firmly secure the cam to the blank for the following grinding and polishing operations.

The invention claimed is:

1. An apparatus for positioning a blanking out cam button on a multifocal lens blank having a boundary line separating its fields, comprising a holder for said blank having a seat for centering the blank thereon, a series of positioning heads each having a surface engageable by the cam button and extending to the surface of the blank, a bracket associated with each of said heads adjustably mounted on said holder, and a universal yielding and adjustable mounting on each of said brackets adapted to support and adjust the respective heads thereon to effect the accurate positioning thereof relative to said boundary line, whereby said heads may receive and position said cam button for alignment therewith.

2. An apparatus for positioning a blanking out undercut cam button on a multifocal lens blank having a boundary line separating its fields and wherein the cam surface of said button is spaced therefrom, comprising a holder for said blank having a seat for centering the blank thereon, a series of positioning heads each having a peripheral surface engageable by the spaced surface of the button and extending to the surface of the blank parallel to the axis thereof, a mounting on said holder for each of said heads, and a radially adjustable support carried by said mountings respectively operable to effect the accurate positioning of said heads on said boundary line for locating the spaced cam surface of the button in projected relation thereto.

3. An apparatus for positioning a blanking out

cam button on a multifocal lens blank having a boundary line separating its fields, comprising a holder for said blank formed to provide a centering seat thereon, a series of brackets adjustably mounted on said holder to extend over the blank when seated thereon, a positioning head associated with each of said brackets, a universal spring pressed mounting adapted to support each of said heads on its respective bracket in surface engagement with the blank, and a screw adjustably supported by each of said brackets operably connected with its respective mounting to effect the setting of the head in alignment with said boundary whereby said heads are adapted to locate the button therebetween in operative relation to said boundary.

4. An apparatus for positioning a blanking out cam button on a multifocal lens blank having a circular boundary line separating its fields, comprising a holder for said blank, a plurality of locating heads mounted on said holder engageable by said button to control the positioning thereof in alignment with a portion of said boundary line, and an adjustable mounting on said holder for each of said heads operable to move them radially of said blank into button aligning position.

5. An apparatus for positioning a blanking out cam button on a multifocal lens blank having an outer vision field and a circular inner vision field, comprising a holder for the blank, a plurality of button locating heads supported by said holder about the outer field of said blank, and means on said holder operable to adjust said heads to a position thereon tangential with the circular boundary line of the inner field to position the button within and in alignment with a portion of said circular boundary line.

6. An apparatus for positioning a blanking out cam button on a multifocal lens blank having an outer vision field and a circular inner vision field, comprising a holder for the blank, a plurality of button locating heads supported by said holder about the outer field of said blank, each of said heads being in the form of a truncated cone having a tapered peripheral button engaging surface, and means on said holder operable to adjust said heads to a position thereon with the base of their respective tapered surfaces tangential with the circular boundary line of the inner field to position the button within and in alignment with a portion of said circular boundary line.

7. An apparatus for positioning a blanking out cam button on a multifocal lens blank having an outer vision field and a circular inner vision field, comprising a holder for the blank, a plurality of button locating heads supported by said holder about the outer field of said blank, each of said heads having a button engaging surface and a blank engaging surface, said button engaging surface extending at an acute angle to the blank engaging surface and parallel to the axis of the blank, and means on said holder operable to adjust said heads to a position thereon with the base of their button engaging surface tangential with the circular boundary line of the inner field to position the button within and in alignment with a portion of said circular boundary line.
